UNITED STATES PATENT OFFICE.

JOSEPH J. AUER AND MAX ROEHMHOLDT, OF BUFFALO, NEW YORK.

CUFF BUTTON.

Application filed February 25, 1924. Serial No. 694,840.

To all whom it may concern:

Be it known that we, JOSEPH J. AUER and MAX ROEHMHOLDT, citizens of the United States, residing at Buffalo, in the county of Erie and State of New York, have invented new and useful Improvements in Cuff Buttons, of which the following is a specification.

This invention relates generally to cuff buttons, but more particularly to that type constructed of separable sections.

Its chief object is to provide a cuff button of this character having simple and reliable means for separably connecting the sections of the button.

Another object of the invention is to provide a separable cuff button whose sections are connected and disconnected by a turning movement of one section relative to the other and in which a dual locking device is employed for positively preventing the sections from accidentally pulling apart and also for resisting the relative turning movement of the sections.

In the accompanying drawings:

Figure 1 is a transverse vertical section on line 1—1, Fig. 2. Figure 2 is a transverse vertical section on line 2—2, Fig. 1. Figures 3 and 4 are horizontal sections on the correspondingly numbered lines in Figs. 1 and 2, respectively. Figure 5 is a perspective view of the locking device or spring plate which forms a part of the socket member of the button. Figure 6 is a horizontal section on line 6—6, Fig. 1.

Similar characters of reference indicate corresponding parts throughout the several views.

The improved button consists of separable sections 10, 11, which are of substantially the same shape, one constituting the stud member and the other constituting the socket member. Each of these members is preferably provided with a hollow head 12 and a flanged base 13 connected therewith by a neck 14 having an opening 15 leading to the interior of said head.

The stud member 10 is provided with a shank or round post 16 which is suitably secured in the opening 15 thereof and which is adapted to enter the corresponding opening in the socket member 11 for detachably connecting said members. The outer or upper end of this post terminates in a reduced flat-sided head 17 of conical form between which and the round portion of the post are

formed oppositely-facing locking notches or grooves 18. In the closed position of the button sections, this head extends into the hollow portion 12 of the socket section. 60

Arranged within the hollow head of the socket member 11 is a locking device, preferably in the form of a plate 19, constructed of sheet metal or similar material, which is held against turning in said member and with which the post 16 of the stud member is adapted to interlock upon inserting it into the socket member and turning one of said members a fraction of a revolution. For this purpose, the locking plate is disposed 70 horizontally in the socket member head and extends across its neck-opening 15, the same being provided with a substantially rectangular opening 20 in line with said neck-opening and of a size to receive the reduced 75 post-head 17 when turned into register therewith. When the stud member is turned to bring its post-head out of register with or at approximately right angles to the plate-opening, the notches 18 thereof interlock 80 with the opposing marginal edges of said opening and prevent separation of the button-sections. As shown in Fig. 1, the plate 19 rests on the bottom of the socket member 85 head 12 and may be provided at its ends with inclined extensions 21 which engage the side walls of said head. In the embodiment of the invention shown in the drawings, this locking plate is securely held in place by clamping it between the marginal 90 rim of the head and its top piece 22.

Means are also provided for yieldingly resisting turning of the stud member relative to the socket member after they are assembled or brought into locking engagement. These means are preferably made an integral part of the plate 19 and consist of opposing spring jaws 23 bent out of the central portion of this plate on either side of its opening 20. As shown in Figs. 1 and 5, these jaws are curved upwardly and thence downwardly and bear against the opposite flat sides of the post-head 17 to resist movement of the latter out of its locked position. To prevent the jaws from being deflected laterally during the relative turning movement of the stud member and socket member, their free or lower ends 24 extend into the plate-opening 20, as clearly shown in Fig. 5. 100

While the post 16 may be securely fastened to its stud member 10 in any well

known manner, we prefer to mount it in the manner shown in Figs. 1 and 2. As there shown, the post is provided at its lower end with a reduced head 23 having notches 26 in its opposite sides. Secured within the hollow head-portion 12 of the stud member is a plate 27 having a rectangular opening 28 with the opposing marginal edges of which the post-head notches 26 are adapted to interlock to prevent longitudinal displacement of said post relative to the stud member. To hold the post against turning, the plate 27 is provided with oppositely-facing jaws or tongues 29 which are adapted to extend into the plate-opening 28 for engagement with the flat sides of the post-head. These jaws are preferably formed integral with said plate and possess the required flexibility to permit them to spring downwardly when the post-head is inserted in the plate-opening while assembling the parts, after which they are forced backward to a substantially horizontal position with their opposing ends abutting firmly against the sides of the post-head, as shown in Fig. 1.

To prevent the post 16 being forced downwardly into the head of the stud member, the same is provided intermediate its ends with an annular shoulder 30 which bears at its underside against the opposing flared end of the neck-opening 15.

In use, the post of the stud member 10 is inserted through the neck-opening of the socket member 11 with its head 17 in position to enter the rectangular opening 20 of the locking plate 19. The stud member is then given a quarter turn to bring its head transversely of the plate-opening, and its notches 18 into locking engagement with the latter. During this operation the spring jaws 23 are at first spread outwardly and then sprung inwardly or toward each other against the flat sides of the post-head. In this position, the two parts of the button are reliably and positively locked against accidental separation. To separate the button members, one of them is simply given a quarter turn relative to the other to bring the post-head 17 longitudinally in line with the plate-opening 20, whereupon the stud member can be readily withdrawn from the socket member.

We claim as our invention:

1. A separable cuff button, comprising a socket member, a stud member, and means contained within said socket member and separate therefrom for detachably receiving said stud member, the latter and said means being provided with complementary interlocking elements which are alternately engaged and disengaged when the stud member is turned a fraction of a revolution relative to the socket member, said means including elements for yieldingly resisting turning of said socket member and said stud member relative to each other.

2. A separable cuff button, comprising a socket member, a stud member, and a locking device contained within said socket member, and having an opening therein for receiving said stud member, the latter being constructed to interlock directly with the opening of said locking device when turned a fraction of a revolution, whereby the stud and socket members are prevented from pulling apart, and said locking device having portions normally bearing against opposite sides of said stud member for yieldingly resisting turning of said members relative to each other.

3. A separable cuff button, comprising a socket member, a stud member having a flat-sided head, complementary interlocking elements on said members which are engaged and disengaged upon turning one of said members relative to the other, and yieldable means carried by said socket member and engaging the opposite flat sides of said stud member for resisting turning thereof.

4. A separable cuff button, comprising a socket member, a stud member having a T-head, a plate mounted on said socket member and having a substantially rectangular opening for detachably receiving the head of said stud member, the latter being constructed to interlock with said plate-opening when turned a fraction of a revolution to prevent said members from pulling apart, and means on said plate at opposite ends of its opening for engaging the sides of the stud member head to resist turning of said members relative to each other.

5. A separable cuff button, comprising a socket member, a stud member having a substantially flat-sided end portion arranged to enter said socket member, said end portion having grooves in its opposite sides adapted to interlock with the socket member when turned a fraction of a revolution, and laterally yieldable jaws contained within said socket member for engagement with the opposite sides of the flat end portion of said stud member for resisting turning thereof out of its locked position.

6. A separable cuff button, comprising a socket member including a part concealed therein having an opening, a stud member including a shank extending through said opening and having notches therein arranged to interlock with the opposing marginal portions of said opening in one position and to be disengaged therefrom when said stud member is turned a fraction of a revolution, and means on the concealed part of the socket member engaging the extended portion of said shank for yieldingly resisting turning of the stud member out of its locked position.

7. A separable cuff button, comprising a stud member having a shank provided near its end with oppositely-facing notches, a

- socket member having an opening for receiving the shank of said stud member, and a plate fitted within said socket member and having an opening therein in line with the 5 opening of said socket member, the notched end of said shank being adapted to extend through and alternately register and interlock with said plate-opening when the stud member is turned a fraction of a revolution, 10 and resilient means formed on said plate at opposite ends of its opening and in engagement with the shank of said stud member for resisting movement thereof out of its locked position.
- 15 8. A separable cuff button, comprising a stud member having a shank provided near its end with oppositely-facing notches, those sides of the shank-end at right angles to 35 those containing said notches having flat bearing faces; a socket member having an opening for receiving the shank of said stud member, and a plate fitted within said socket member and having an opening therein in line with the opening of said 40 socket member, the notched end of said shank being adapted to extend through and alternately register and interlock with said plate-opening when the stud member is 45 turned a fraction of a revolution, and opposing spring-jaws bent from said plate for engagement with the flat-bearing faces of the shank of said stud member, the free ends of said spring-jaws extending through 50 said plate-opening.
- 20 10. A cuff button, comprising separable sections rotatable relatively to each other, one section carrying a post adapted for interlocking engagement with the other section, said post being provided at its opposite ends with notched heads, and plates fitted in said sections having openings therein for receiving the notched-heads of said post, that plate contained in the section carrying 55 the post being constructed to interlock with the latter to hold it against longitudinal and rotary movement relative to such section, while the plate contained in the other section is constructed to releasably engage the 60 other end of said post.
- 25 9. A separable cuff button, comprising a stud member having a shank provided near its end with oppositely-facing notches, those 30
